PENCIL CASE

Jack Fairchild Fleming, Summit, N.J., assignor to Sterling
Plastics Co., Union, N.J., a corporation of New Jersey

Filed Oct. 25, 1960, Ser. No. 62,758

Term of patent 14 years

(Cl. D74—21)

Fig. 1 is a top perspective view of a pencil case embodying my new design;

Fig. 2 is a similar view thereof as it appears with the cover in open position;

Fig. 3 is an end elevational view as seen from the right of Fig. 1;

Fig. 4 is an end elevational view as seen from the left of Fig. 1; and

Fig. 5 is a side elevational view thereof, the side opposite thereto being similar in appearance.

I claim:

The ornamental design for a pencil case, substantially as shown and described.
